(57) CLAIM

The ornamental design for a display screen or portion thereof with icon, as shown and described.

DESCRIPTION

FIG. 1 is a front view of a display screen or portion thereof with icon of our new design; and,

FIG. 2 is a second embodiment thereof.

The broken lines showing a display screen or portion thereof illustrate portions of the article and do not form part of the claimed design.

1 Claim, 2 Drawing SheetsFIG. 1

FIG. 2
